Attorney—Sughrue, Rothwell, Mion, Zinn & Macpeak[57] ABSTRACT
A circuit breaker comprising a hollow insulating column, and an insulated cut-off chamber supported by the column and having movable and fixed contact members therein that are connected to terminals. An optical link current transformer is also provided and comprises a polarized light beam transmitter arranged at the bottom of the column which transmits a beam to the interior of the column, an optical Faraday element, and a toroidal winding directly securing one of the terminals connected to the contact members. The Faraday element is connected to the toroidal winding so as to be subjected to magnetic fields generated by current in the winding. Reflecting mirrors are provided in the column and in the cut-off chamber for transmitting light beams from the transmitter through the column and cut-off chamber and to the Faraday element. Additional reflecting mirrors are provided to transmit light beams from the Faraday element back through the cut-off chamber, the column and then to a photoelectric cell arranged at the base of the column.

CIRCUIT BREAKER HAVING CURRENT TRANSFORMER WITH INCORPORATED OPTICAL LINK

BACKGROUND OF THE INVENTION

This invention relates to an electrical circuit breaker involving a current transformer with incorporated optical link.

The invention applies to a circuit breaker involving a hollow insulating column supporting at least one chamber in which are arranged cut-off members connected to connection conductors traversing the walls of said chamber in insulating terminals.

It is known, for example, on the basis of U.S. Pat. No. 3,324,393, that one can associate a circuit breaker, thus constituted, with an optical current transformer involving the following elements:

A polarized light beam emitter, arranged at the bottom of the column, means for transmitting the beam to the interior of the column up to the input of an optical Faraday element subjected to the magnetic field created by a coil connected to a toroidal winding in whose axis passes one of the above-mentioned connection conductors, and means for conducting the light beam, coming out of said Faraday element, into the hollow column, up to a photoelectric cell arranged at the base of the column.

However, in such a circuit breaker, the magnetic torus is arranged around the output terminal of the connection conductor, which requires it to have a large diameter, and it is therefore expensive to make and it is subject to heavy losses.

SUMMARY OF THE INVENTION

The circuit breaker according to the invention differs from the above-described known circuit breaker by the fact that the magnetic torus is arranged directly around the connection conductor. Instead of being outside an insulating enclosure, for example, made of porcelain, it is positioned inside the enclosure.

This enclosure may be an auxiliary chamber attached to the cut-off chamber or it may be made up of the cut-off chamber itself, with the input and output light beams then running parallel to the contact pieces arranged in the chamber or even inside the contact pieces, if the latter are hollow.

In the case where two cut-off chambers are supported by the same insulating column, the circuit breaker according to the invention may involve a single light beam source at the base of the column and reflecting means for sending the beam toward two "Faraday elements—magnetic torus" assemblies associated respectively, with the two chambers, and to return the output beam of the assemblies toward photoelectric cells.

Likewise, according to the invention, when the column and/or the cut-off chambers are filled with a relatively opaque liquid, such as oil, tubes filled with air may be arranged in the column and/or chambers for the passage of the light beams.

BRIEF DESCRIPTION OF THE DRAWINGS

FIGS. 1 and 2 are elevational views, partly in section and with parts broken away;

FIG. 3 is a schematic view showing a first embodiment of this invention;

FIG. 4 is an elevational view, partly in section and with parts broken away;

FIG. 5 is a schematic view of a second embodiment of the invention; and

FIG. 6 is an elevational view, partly in section and with parts broken away, of a third embodiment of the invention.

FIG. 1 is a partial cross-section view along axis AB in FIG. 2 and FIG. 2 is a partial cross-section view along axis CD in FIG. 1, showing the first form of the invention with the auxiliary chamber for the transmission of light beams.

DESCRIPTION OF THE PREFERRED EMBODIMENTS

In the drawings, and particularly in FIGS. 1 and 2, FIG. 1 refers to a base enclosure supporting a hollow insulating column 2, the latter in turn supporting a lateral cut-off chamber 3 containing the fixed contact piece 4 and the movable contact piece 5 of the circuit breaker, and the control rod system 6 for the movable contact piece.

To the base enclosure 1 there are connected, on the one hand, a polarized light emission device, designated overall by 7, of a type well known in the art, and, on the other hand, a light reception device, designated by 8, comprising, in the known manner, a photoelectric cell associated with an amplifier.

The light emission and reception devices, 7 and 8, respectively, are in communication with the enclosure 1 by means of transparent fittings 9 and 10, respectively.

The incident light beam from the light emission device 7 is sent into the hollow column 2 by a mirror 11, through a transparent fitting 15, and falls upon a mirror 12 which reflects it into an auxiliary chamber 13, parallel to the cut-off chamber 3.

At the end of this chamber 13, the beam is reflected by a mirror 14 in the input of a Faraday-effect element, as shown in FIG. 3. This device comprises, in a known manner, a transparent cylinder 16 made of flint glass, on whose ends are glued, respectively, a polarizer element and an analyzer element, and it is placed in the magnetic field of a coil 17 supplied by a secondary winding of a current transformer 18 in the forms of a torus which, according to the invention, and contrary to the prior art, is arranged directly around a terminal 19, connected to fixed contact 4 of the circuit breaker.

The light beam, coming out of the Faraday-effect element, is reflected, by mirrors 20, 21 and 22, to the photoelectric cell of the light reception device 8.

FIGS. 4 and 5 show, schematically, one variant of the application of the optical-link current transformer with circuit breaker having two cut-off chambers 3 and 3₁, carried by a single column 2.

This variant involves a single light beam transmitter, identical to the one in FIG. 1, and which has therefore not been shown here, and an auxiliary enclosure 23 attached to the assembly of the two cut-off chambers.

In this auxiliary enclosure, the incident light beam falls upon a semitransparent mirror 24; a portion of said beam is reflected by this mirror 24, by means of another mirror 25, toward a Faraday-effect device, shown schematically at 26, and subjected to the action of a current from the terminal 19, coming out of chamber 3. The other portion of the beam, which has

traversed the mirror 24, falls upon a mirror 28 which reflects it back, by means of another mirror 25₁, toward a second Faraday-effect device 26₁, associated with terminal 19₁ or chamber 3₁.

The beams coming out of the two Faraday-effect devices, after reflection by mirrors 29, 29₁, fall, respectively, on two mirrors 30, 30₁, which send them back toward two beam reception devices identical to the reception device 8 according to FIG. 1, and which therefore are not shown in FIGS. 4 and 5.

In another variant, the light beams are transmitted into the cut-off chamber 3 itself, instead of being transmitted into an auxiliary chamber parallel to the cut-off chamber. They are then transmitted parallel to the contact pieces 4 and 5, either outside them or, if said contact pieces are hollow as shown in FIG. 6, inside the latter.

Finally, it must be noted that, in the case where the column 2 is filled with a fluid that is opaque, for example, oil, tubes filled with air, such as 31 shown in FIG. 4, may be arranged in said column, one tube for the outgoing beam and one tube for the return beam.

I claim:

1. In an electrical circuit breaker comprising:
a hollow insulating column,
an insulated cut-off chamber supported at one of its ends by said column and having movable and fixed contact members therein,
at least one terminal connected to said contact members at the other end of said chamber,
an optical link current transformer comprising a light beam transmitter, arranged at the bottom of said column,
means for transmitting this beam to the interior of said column,
an optical Faraday element,
a toroidal winding surrounding said terminal,
means for subjecting said Faraday element to a magnetic field, generated by current in said winding,
means for transmitting said light beam to said Faraday element,
a photoelectric cell arranged at the base of said column, and
means for conducting the light beam coming out of

45

said Faraday element through said column and to said photoelectric cell; the improvement wherein said toroidal winding directly surrounds said terminal, said optical Faraday element is located close to said terminal and said column is filled with a relatively opaque liquid and tubes are arranged in said column for the passage of light beams.

2. In an electrical circuit breaker comprising:
a hollow insulating column,
an insulated cut-off chamber supported at one of its ends by said column and having movable and fixed contact members therein,
at least one terminal connected to said contact members at the other end of said chamber,
an optical link current transformer comprising a light beam transmitter, arranged at the bottom of said column,
means for transmitting this beam to the interior of said column,
an optical Faraday element,
a toroidal winding surrounding said terminal,
means for subjecting said Faraday element to a magnetic field generated by current in said winding,
means for transmitting said light beam to said Faraday element,
a photoelectric cell arranged at the base of said column, and
means for conducting the light beam coming out of said Faraday element through said column and to said photoelectric cell; the improvement wherein said toroidal winding directly surrounds said terminal, said optical Faraday element is located close to said terminal, two cut-off chambers are supported by the insulating column; wherein contact members, terminals, a Faraday element and a toroidal winding are associated with each of said chambers; and wherein a semireflecting mirror is provided for the purpose of reflecting to each chamber the light beam issuing from said transmitter arranged at the bottom of said column, and reflecting mirrors are provided for the purpose of reflecting the output light beams from each of the chambers toward said photoelectric cell arranged at the base of said column.
